UNITED STATES PATENT OFFICE

MAX KUSHNER, OF CLEVELAND, OHIO

DOOR CLOSER

Application filed January 13, 1933. Serial No. 651,533.

This invention relates to door closers and has for its object to provide a simple and inexpensive device for automatically returning a door to closed position, which employs no springs and which is actuated solely by fluid pressure.

A further object of the invention is to provide a door closer in which the actuating mechanism operates against fluid pressure when moved in either direction from a neutral position and is adapted to be applied without alteration or adjustment to either right or left hand doors, and which is suitable for use on doors mounted to swing either in or out.

A further object of the invention is to provide a fluid pressure actuating device in the form of a small compact unit adapted to be mounted on a door or door casing, which is capable of developing ample power for positively closing the door and which is capable of operation for a long period of time without attention.

A further object of the invention is to make the action of the fluid pressure device more positive and to eliminate leakage by employing a flexible actuating diaphragm, and further to provide means for so guiding and supporting the diaphragm that the diaphragm is not distorted or subjected to excessive stresses in transmitting its thrust to the door actuating connections or in receiving the thrust of the door actuating connections.

A further object of the invention is to provide a compactly housed door closing mechanism which comprises few parts, which can be quickly and easily assembled or taken apart.

With the above and other objects in view the invention may be said to comprise the device as illustrated in the accompanying drawing hereinafter described and particularly set forth in the appended claims, together with such variations and modifications thereof as will be apparent to one skilled in the art to which the invention appertains.

Reference should be had to the accom-

panying drawing forming a part of this specification, in which:

Figure 1 is a fragmentary front elevation showing the door closer of the present invention applied to the door, the interior actuating mechanism being shown in dotted lines;

Fig. 2 is a top plan view of the actuating unit;

Fig. 3 is a section taken on the line indicated at 3—3 in Fig. 1.

In the accompanying drawing, there is shown a door closer embodying the present invention in which the actuating unit is in the form of an air tight housing 1 provided with attaching flanges 2 by which it may be secured to a door 3. Journalled in the upper end of the housing 1 there is a shaft 4 to which is fixed an actuating arm 5 which is connected by a link 6 to a bracket 7 attached to a door lintel 8.

As is common practice in door closing devices, the actuating arm 5 is turned, and with it the shaft 3 and mechanism actuated thereby upon the opening of the door and the power exerted upon the arm 5 during the opening movement is stored in the actuating mechanism and is exerted in the opposite direction upon release of the door to swing the door to closed position.

The housing 1 has a cup shaped bottom section 9 which is provided with an outwardly projecting peripheral flange 10 at the top thereof and a tubular top section 11 which is provided with a peripheral outwardly projecting flange 12 at its lower end which is attached to the flange 10 of the bottom section by means of bolts 13. The upper end of the housing 1 is closed by a head 12 which is secured by bolts 15 to the upper end of the tubular section 11.

A flexible diaphragm 16 in the form of a cupped disk is clamped at its margin between the flanges 10 and 12 of the lower and upper sections of the housing, and provides within the housing two airtight chambers 17 and 18. The lower chamber 17 contains a liquid such as glycerin, preferably in an amount to substantially fill the chamber when the diaphragm 16 is in its lowermost

position. The upper chamber 18 is partially filled by the liquid 20, such as glycerin, the amount of liquid in the upper chamber being preferably somewhat less than the capacity of the chamber when the diaphragm 16 is in its uppermost position so as not to interfere with the movement of the diaphragm throughout its entire range. The diaphragm 16 is impervious to the passage of air or liquid, and preferably consists of an interior rubber disk 21 and upper and lower disks 22 of leather attached to the rubber disk. The diaphragm 16 is of dished or cup form so that the central portion thereof may be moved vertically from a downwardly bowed to an upwardly bowed position.

Since fluid pressure acting upon the diaphragm 16 is transmitted to the door actuating mechanism and the mechanism exerts a direct thrust upon the diaphragm in opposition to the fluid pressure acting thereon, it is important that means be provided for preventing distortion of the diaphragm which would create local stresses in the material thereof due to the mechanical thrust, and that means be provided for limiting the vertical movements of the central portion of the diaphragm to avoid excessive tensile stresses thereon. For guiding, supporting and limiting the movement of the central portion of the diaphragm, a piston 23 is clamped against the under side of the central portion of the diaphragm by means of a bolt 24 which extends through the diaphragm and piston, which has a shoulder 25 engaging the top of the diaphragm, a projecting head 26 above the shoulder 25 and a nut 27 at its lower end which is positioned in a recess on the under side of the piston. The piston 23 may engage the bottom of the housing section 9 to limit the downward movement of the diaphragm and is provided with passages 28 to allow passage of liquid from the under side of the piston to the upper side thereof during the descent of the piston, and passage of liquid to the under side of the piston during the upward movement of the piston.

The actuating shaft 4 extends through the head 14 into the upper chamber 18 and is journalled in a boss 29 formed integrally with the head 14. Leakage of air or liquid through the shaft bearing is prevented by a packing 30 within the boss 29. The upper end of the shaft 4 is splined to receive the arm 5 so that the arm 5 may be angularly adjusted upon the shaft. Fixed to the lower end of the shaft 3 within the chamber 18, there is fixed a bevel pinion 32 which meshes with a bevel gear 33 rotatably mounted on a stub shaft 34 which is secured by a pin 35 in a boss 36 formed integrally with the wall of the upper section 11 of the housing. The boss 36 is bored to receive shaft 34, and the outer end of the bore may be closed

by a threaded plug 39 which prevents escape of air or liquid from the chamber. The bevel gear 33 has rigidly secured thereto an eccentric pin which projects from the inner face of the gear. To this pin is pivoted the upper end of the link 39, which is connected at its lower end by a pivot pin 40, to the projecting end 26 of the bolt 24. The link 39 is of a length such that when the piston 23 is substantially in engagement with the bottom of the housing, the pin 38 is in dead center position directly below the shaft 34. It will be apparent that from this dead center position the piston 23 and diaphragm 16 will be raised upon rotating movement of the shaft 3 in either direction, so that by properly positioning the arm 5 on the shaft 3 the device may be applied either to a right hand or a left hand door.

It will also be apparent that if the pin 38 is in dead center position when the door is closed, the door may swing in either direction from its closed position, and upon opening of the door in either direction the diaphragm will be raised, creating a vacuum in the chamber 17 and subjecting the air in chamber 18 to pressure, developing a fluid pressure upon the diaphragm 16 which will be effective to return the door to closed position.

Door closers are more often applied, however, to doors opening in one direction only, and in some instances considerable pressure is required at the end of the closing movement to latch the door. When a final closing pressure is necessary, it may be obtained in the device of the present invention by adjusting the arm 5 so that the piston 23 is slightly above the bottom of the housing in the closed position of the door.

In order to prevent slamming of the door, means is provided for checking the final closing movement. The checking device is a dash pot consisting of a small cylinder 41 formed integrally with the wall and the housing section 11, and this cylinder is provided with an inlet opening 42 in its wall above the bottom of the cylinder and with an outlet opening 43 in the bottom of the cylinder. A regulating screw 44 projects into the opening 43. This screw is provided with a head 45 outside the housing and with a lock nut 46 by which it may be secured in adjusted position. By means of the screw 44, the size of the outlet opening 43 may be regulated as desired. The piston 47 is mounted to slide in the cylinder 41, and to the upper end of this piston there is rigidly secured an L-shaped arm which is attached at its lower end to the pivot pin 40, so that the piston 47 is caused to move upwardly and downwardly with the diaphragm.

When a door is swung to open position the piston 47 is raised above the inlet 42, the liquid flows from the chamber 18 to the in-

terior of the cylinder 41. During the closing movement of the door, the piston 47 moves down past the inlet 42, and after the inlet 42 is closed by the piston a body of liquid is trapped at the lower end of the cylinder 41. The trapped liquid escapes through the opening 43 which may be adjusted to regulate the speed of movement of the piston 47 and consequently the speed 10 of movement of the door as it approaches closing position. There is a fluid pressure resisting the initial upward movement of the piston 47 as the door is being opened due to the small size of the opening 43, but since 15 the piston 47 is a very small piston the added drag upon the door during its initial opening movement due to this piston will be very slight.

When the door 3 is in closed position the 20 piston 23 and eccentric pin 38 are at or near their lowermost positions as shown in Figs. 1 and 3. Movement of the door 3 toward open position actuates arm 5, shaft 4 and pinion 32 to turn the gear 33 in a clockwise 25 direction as viewed in Fig. 1, elevating the link 39 and the central portion of the diaphragm 16 to which the link is attached. Upward movement of the diaphragm 16 increases the volume of the chamber 17 which 30 tends to create a vacuum. At the same time the volume of the chamber 18 is diminished, putting the air above the surface of the liquid under compression. The opening of the door thus imposes a fluid pressure on the 35 diaphragm 16 due principally to sub-atmospheric pressure in the lower chamber 17 and to some extent to compression of the air in the top of the chamber 18. Upon release of the door this fluid pressure on the diaphragm 40 acts to force the diaphragm back to its original position and close the door.

In assembling the device, the piston 23 with the diaphragm 16 attached thereto by the bolt 24 is placed in the lower housing 45 section 9 and with the piston 23 resting on the bottom the space beneath the diaphragm is filled with a liquid such as glycerin, and the upper section 11 is then clamped upon the margin of the diaphragm. The gear 33 and link 39 and the piston 47 and arm 48 50 may be assembled together and mounted within the section 11 either before or after attachment of the section 11 to the section 9. The link 39 and arm 48 are then attached to the projecting head 26 of the bolt 24 by means of the pin 40. The chamber 18 is then filled to the desired height with a liquid such as glycerin, after which the head 14 with shaft 4 and pinion 32 in place thereon is secured to the upper end of the section 55 11.

The chamber 17 is quite effectively sealed by reason of the fact that the margin of the diaphragm is tightly clamped between the flanges 10 and 12, by reason of the fact that 60

the top of the diaphragm is covered at all times with liquid and by reason of the fact that the diaphragm is so constructed that it is impervious to passage of liquid through the body thereof. The diaphragm thus provides a movable actuator directly subjected to fluid pressure which is not subject to loss of effectiveness due to leakage of fluid past the actuator, a difficulty inherent in actuators of the sliding piston type. 70

Since a nearly perfect vacuum is quickly established beneath the diaphragm 16 upon upward movement thereof a heavy thrust is quickly imposed on the gear 33 and connecting link 39. The material of the diaphragm 16 is not, however, subjected to excessive stresses due to the fact that the link is connected to the diaphragm through the bolt 24 which clamps the diaphragm to the piston 23 which guides the movement of the 80 central portion of the diaphragm. 85

The lower chamber 17 is the main actuating chamber from which entry of air or liquid is positively excluded. It is not necessary, however, that special packing or 90 other means be provided for keeping the chamber 18 absolutely air tight, since slow leakage of air into or out of the upper portion of the chamber 18 will not materially affect the operation, the pressure of the air 95 above the liquid being at substantially atmospheric pressure when the door is closed.

The bevel gearing and connecting link within the upper chamber 18 are effectively lubricated by the liquid in the chamber and due to the fact that nearly full atmospheric pressure is effective on the diaphragm throughout its range of movement, the diaphragm need have only a small range of movement. The entire mechanism can, 100 therefore, be housed within a small compact housing and will operate effectively for 105 long periods without attention.

What I claim is:

1. In a door closer, a casing, a shaft having an actuating arm outside the casing and journaled in the casing at one end thereof, an airtight chamber within the casing having a wall in the form of a flexible diaphragm having a linearly movable central portion, and motion transmitting means interconnecting the shaft and diaphragm for actuation either by the other and acting torsionally on the shaft and linearly on the movable portion of the diaphragm. 110

2. In a door closer, an angularly movable shaft having an actuating arm attached thereto, a fluid tight chamber spaced from an end of the shaft and having a flexible diaphragm wall which has a central portion 115 movable linearly in the direction of the shaft axis, and means interconnecting the angularly movable shaft and axially movable portion of the diaphragm for actuation either by the other. 120

3. In a door closer, an angularly movable shaft having an actuating arm attached thereto, a fluid tight chamber spaced from an end of the shaft and having a flexible diaphragm wall which has a central portion movable linearly in the direction of the shaft axis, a piston slideable within said chamber and clamped against the central portion of said diaphragm, and means interconnecting the angularly movable shaft and axially movable portion of the diaphragm for actuation either by the other.

4. In a door closer, an angularly movable shaft having an actuating arm attached thereto, a fluid tight chamber spaced from an end of the shaft and having a flexible diaphragm wall which has a central portion movable linearly in the direction of the shaft axis, a dash pot connected to the movable portion of the diaphragm for retarding the movement of the diaphragm in one direction, and means interconnecting the angularly movable shaft and axially movable portion of the diaphragm for actuation either by the other.

5. In a door closer, a casing, a flexible diaphragm forming a partition between upper and lower chambers in said casing and having a vertically movable central portion, said chambers being partially filled with liquid, an axially disposed shaft journalled in the upper end wall of the casing and projecting into the upper of said chambers, a dash pot device for retarding movement of the diaphragm in one direction including a cylinder in one of said chambers having an inlet to receive liquid from the chamber, a piston and an outlet, means accessible from the exterior of the casing for varying the size of the discharge opening, and means interconnecting the angularly movable shaft and vertically movable portion of the diaphragm for actuation either by the other.

6. In a door closer, a casing, a flexible diaphragm forming a partition between upper and lower chambers in said casing and having a vertically movable central portion, said chambers being partially filled with liquid, an axially disposed shaft journalled in the upper end wall of the casing and projecting into the upper of said chambers, gears disposed in driving relation within the upper chamber, one of said gears being fixed to said shaft, and a link connected to the central portion of said diaphragm and eccentrically to one of said gears.

7. In a door closer, a casing, a flexible diaphragm forming a partition between upper and lower chambers in said casing and having a vertically movable central portion, said chambers being partially filled with liquid, an axially disposed shaft journalled in the upper end wall of the casing and projecting into the upper of said chambers, a piston in the lower chamber rigidly con-

nected to the central portion of the diaphragm, a member rigidly connected to the piston and projecting into the upper chamber, a link pivoted at its lower end to said projecting member, and an actuating means interposed between said link and said shaft.

8. In a door closer, a casing, a flexible diaphragm forming a partition between upper and lower chambers in said casing and having a vertically movable central portion, said chambers being partially filled with liquid, an axially disposed shaft journalled in the upper end wall of the casing and projecting into the upper of said chambers, a piston in the lower chamber rigidly connected to the central portion of the diaphragm, a member rigidly connected to the piston and projecting into the upper chamber, a bevel pinion fixed to the lower end of said shaft, a bevel gear meshing with said pinion, and a link pivoted at its lower end to said projecting member and at its upper end eccentrically to said gear.

In testimony whereof I affix my signature.
